WOOD PLANER CUTTER HEAD WITH REMOVABLE BITS

Jesse L. Spencer, Jr., 2401 Ellington St., and John S. Stewart, 2004 Cedarfork Drive, both of Greensboro, N.C. 27403

Filed Sept. 23, 1974, Ser. No. 508,093

Term of patent 14 years

Int. Cl. D15—09

U.S. Cl. D55—1 A

FIG. 1

FIG. 2

FIG. 3

FIG. 1 is a front view of a wood planer cutter head with removable bits incorporating our invention;

FIG. 2 is a left end enlarged view of FIG. 1;

FIG. 3 is an enlarged partial transverse sectional view along line 3—3 of FIG. 1 illustrating the removable bit. The right end view will be similar to the left end view. We claim:

The ornamental design for a wood planer cutter head with removable bits, as shown and described.
